UNITED STATES PATENT OFFICE.

ALPHA LEON DAVENPORT AND ARTHUR JOHN JAMES, OF VANCOUVER, BRITISH COLUMBIA, CANADA.

DOOR-LOCKING DEVICE.

Application filed August 7, 1922. Serial No. 580,296.

To all whom it may concern:

Be it known that we, ALPHA LEON DAVENPORT and ARTHUR JOHN JAMES, both citizens of the United States, and both residing at the city of Vancouver, in the Province of British Columbia, Canada, have invented certain new and useful Improvements in Door-Locking Devices, of which the following is a specification.

10 Our invention relates to improvements in door locking devices and the object of our invention is to provide a device of this character which is so constructed that it may be rendered inoperative to prevent the lock 15 with which it is used being opened by any unauthorized person. A particular object is to devise a locking means capable of being used to great advantage with the form of lock fully described and claimed in Letters Patent of the United States No. 1356604, granted to us on the 26th day of October, 1920 and which enables the complete lock to be greatly simplified and rendered more inexpensive.

25 We attain these objects by the construction illustrated by the accompanying drawings in which—

Fig. 1 is a longitudinal sectional elevation of the lock with which the device is 30 used.

Fig. 2 is a detail view of the locking spindle.

Figs. 3 and 4 are face views of the escutcheon plates.

35 Fig. 5 is a perspective view of the device assembled.

Fig. 6 is a detail view in perspective of the rollback.

Similar figures of reference indicate similar parts throughout the several views.

40 In order to more clearly understand the invention the lock construction shown in Fig. 1 will be briefly described; an extended description, however, will be found in the Letters Patent above mentioned.

45 Referring to Fig. 1, the lock consists of a tubular cylinder 1 having on its outer end a flange 2 having holes through which screws may be passed to secure the lock to the door. The cylinder is closed at its inner end by a cap or plug 3 and slidably mounted in the bore of the cylinder is the lock bolt 4 the outer end of which projects normally beyond the flange 2 while its inner end is recessed as at 5 and bears on the

end of a tension spring 6 disposed between the end of the bolt and the plug 3. The bolt is guided in its travel during projection and retraction by means of keys or lugs 7 and 8 fitting slidably in slots 9 and 10 formed in the cylinder 1, and up to this point the construction is substantially similar to that described in the Letters Patent above mentioned.

Referring now to Fig. 1 in conjunction with the remaining figures, 11 indicates a tongue the ends of which are mounted in the slots 9 and 10, which tongue is provided with side bosses 12 and 13 through which extends a bore 14, these bosses forming bearings resting in a recess 15 formed in the bolt and the cylinder to support the tongue in a substantially vertical position so that its upper and lower rear edges may respectively engage the lock bolt as the tongue is operated. The rear wall of the bore 14 is depressed to form a substantially semi-circular groove 16, the bore being then crescent shape in cross section and through this bore extends the handle spindle 17 which is also crescent shaped in cross section or in other words has a longitudinally extending semi-circular groove 18 adapted to fit over the semi-circular depression formed in the bore by the wall of the groove 16 so that the tongue may therefore be operated by the turning of the handle, suitable knobs 19 and 20, of course, being provided on each end of the spindle on the outer side of the respective escutcheon plates 21 and 22.

20 90 95 100 105 110 23 indicates the locking spindle which, when assembled, lies in the groove 18 of the handle spindle and extends through the lock and both escutcheon plates into each knob, the end projecting into knob 19 being formed in any approved manner so that it may be engaged and turned by a suitable key 24 inserted into a keyhole in the knob, this being the knob on the outside of the door. The opposite end of the spindle 23 which projects into knob 20, or the one on the inside of the door, is preferably connected by any suitable means to a small handle 25 which rests permanently on the outer end of the knob and which takes the place, on the inside of the door, of the outside key 24, from which it will be seen that the spindle 23 may be operated from both ends, when required. The spindle, where it passes through the groove 16 is truly circular, as at 26, so as to be

freely rotatable therein, but where it passes through the bores of the respective escutcheon plate bosses 27 and 28 it is enlarged, as at 29 and 30, these enlargements being 5 formed circular for the major portion of their circumference while the remaining portion is flattened, as shown at 31 in Figs. 2, 3 and 4. Each escutcheon plate bore is provided with a groove, indicated by the numerals 32 and 33 respectively, extending through it in which the respective enlargements 29 and 30 are adapted to be seated, as hereinafter described and as shown in Figs. 3, 4, and 5.

15 The manner in which the device is operated may be described briefly as follows. In placing the lock and the locking device on a door a hole is bored in the edge slightly larger in diameter and length than the cylinder 1 and in the hole the cylinder with the lock bolt and tongue in place, is inserted, the handle spindle having first been withdrawn. The handle spindle, with the locking spindle seated in the groove 18, is 20 then passed through the lock from side to side, the handle spindle passing through the crescent shaped bore 14 and the locking spindle passing through the groove 16 so that its reduced circular portion 26 rests therein. 25 after which the escutcheon plates and the knobs are secured in place.

It will now be seen that, as the locking spindle is capable of independent rotation, it may be turned to bring the circular portions of its enlargements 29 and 30 to lie in the respective grooves 32 and 33 of the escutcheon plates as shown in Figs. 3 and 5 so that the lock bolt cannot then be retracted and the door opened as the engagement of 35 the enlargements 29 and 30 in their respective grooves 32 and 33 prevents the turning of the handle. If, however, the locking spindle be turned to bring the enlargements 29

and 30 to lie in the handle spindle groove 18, the flattened portions 31 being then opposite the grooves 32 and 33 of the escutcheon plates, the handle may be turned to open the door since the spindle 17 is then capable of turning freely the amount necessary to retract the bolt. Thus by turning the locking 45 spindle 23 to carry its circular enlarged portions into or out of engagement with the escutcheon plate grooves the handle spindle may be respectively locked or unlocked.

From the foregoing it will be seen that we 50 have devised a simple, inexpensive, and highly practical door locking device.

What we claim as our invention is:

1. A door locking device comprising a handle spindle having a semi-circular groove 60 extending longitudinally of it, escutcheon plates through which said spindle passes each having a semi-circular groove in its bore, and a rotatable annular locking spindle seated in said handle spindle groove and 65 extending through said escutcheon plate grooves, said spindle being flattened where it passes through said plates.

2. A door locking device comprising a handle spindle having a semi-circular groove 70 extending longitudinally of it and provided on each end with operating knobs, escutcheon plates through which said spindle passes each having a semi-circular groove in its bore, a rotatable annular locking spindle 75 seated in said handle spindle groove, and extending through said escutcheon plate grooves, said spindle being flattened where it passes through said plates, and means for operating said locking spindle independently of said handle spindle.

In testimony whereof we affix our signatures at Vancouver, B. C. this 27th day of July, 1922.

ALPHA LEON DAVENPORT.
ARTHUR JOHN JAMES.
